UNITED STATES PATENT OFFICE.

ORVIL G. LEMMER, OF SEATTLE, WASHINGTON.

WARDROBE TRUNK.

Application filed January 28, 1927. Serial No. 164,333.

This invention relates to an improvement in trunks of the wardrobe type and is particularly directed to improving the constructions shown in United States Letters 5 Patent Nos. 1,292,490 and 1,363,134, issued to me January 28, 1919, and December 21, 1920, respectively.

The principal object of the present invention is to provide a trunk structure in which 10 there will be combined an accepted type of wardrobe trunk and a serviceable type of compartment trunk, with means for adjusting the compartment section to vary the available space in the wardrobe section at 15 will.

The invention is illustrated in the accompanying drawings, in which:

Figure 1 is a plan view of the trunk in 20 open position.

Figure 2 is a front view of the same.

Figure 3 is a fragmentary view partly in section, showing the garment hangers and the retaining gates for holding the garments on said hangers in position.

Figure 4 is a broken top plan view of the 25 garment hangers and their supports.

Figure 5 is a side elevation showing the 30 garment hangers and their supports, together with the means for supporting the gates.

Figure 6 is a front elevational view 35 through the wardrobe section, showing more particularly the compartment section of the trunk, the bottom walls of the compartments being shown in extended positions and the compartment closure in its outermost position.

Figure 7 is a similar view with the compartments shown in reduced size by adjustment 40 of the parts, the gates for the garments on the hangers being shown in position.

Figure 8 is a sectional view through one 45 edge of the gate, showing particularly the supporting member therefor.

Figure 9 is a broken plan of one of the members of the hinge for supporting the gate.

The improved trunk is made up of a substantially rectangular section 1, hereinafter termed the wardrobe section, and a section 2 hingedly connected at 3 to the wardrobe section, said section 2 being hereinafter termed the drawer section. The section 2 50 is of less height than the section 1 and are connected with the top walls of both sections

in the same plane, so that the lower portion 4 of the wardrobe section is of the full sectional area of the trunk when closed to thereby provide a compartment 5 which is 60 closed by the bottom 6 of the drawer section when the latter is in closed relation to the wardrobe section. The top wall of the wardrobe section is cut away in correspondence with the size and shape of the top of the drawer section to secure the proper relation of the sections when closed. The lock 7 is arranged to secure the sections in closed position.

The drawer section is divided by transverse partitions 8 to provide spaces to receive independent drawers 9 which are locked in closed position by a bar 10 hingedly connected for vertical and swinging movement at 11. The bar 10 is recessed at 70 12 to cooperate with projections 13 on the edges of the upper and lowermost partitions 8, the recesses permitting the bar to be moved within the projections which at their entrant ends are spaced apart in correspondence with the width of the bar between the partitions. Following the movement of the bar within the projections, it may be moved up or down to dispose the wide portion of the bar in line with the 75 narrow entrance between the projections, thus preventing removal of the bar. Of course, appropriate locking means of any desired type (not shown) is arranged to hold the bar in its final position, and as the bar overlies all the drawers, said drawers are locked against opening when the bar is 80 in locking position.

Longitudinally of one side wall of the wardrobe section and near the upper edge 95 is secured a channeled frame bar 14 over which is slidably fitted a frame member 15 carrying a depending strip 16 provided near its lower end and at an intermediate point with hinged brackets 17 and 18. Secured to the member 15 is a runner 19, the upper and lower edges of which are undercut to slidably receive a plurality of garment hanger slides 20 provided with brackets 21 between which are pivotally supported sockets 22 to 100 receive the ends 23 of a garment hanger 24 of the usual type. The sockets 22 have entrant ends corresponding to the dimensions of the ends 24 of the garment hangers, the bottom walls of the sockets being downwardly and inwardly inclined from such entrant ends, as at 25.

The upper edges of the ends 23 of the garment hangers are provided with pins 26 adapted to seat in openings 27 in the upper walls of the sockets. This construction permits the garment hangers to be removably connected to the sockets as long as the hangers are in horizontal relation and yet readily removed from the sockets by tilting. The opposite ends of the garment hangers 24 are slidably supported on sliding brackets 28 on the opposite wall of the wardrobe section, the mountings of such ends of the garment hangers permitting their bodily sliding movement or their separation from the mountings for independent swinging through the pivotal support of the sockets at their opposite ends.

A gate 29 is supported on hinged brackets 17 and 18. This gate has projecting hinge members 30 and 31 adapted to be passed through any one of a plurality of openings 32 in the brackets 17 and 18. The openings 32 in the bracket 18 are of keyhole form opening through the edge of the bracket 25 and the hinge member 30 has a laterally bent free end 33 to pass through the reduced portion of the openings 32 in the bracket 18. Thus, when in operative position, the gate cannot be disconnected. The gate has a locking member 34 having rearwardly extending upper and lower projections 35 adapted to be pivotally connected to lateral projections 36 at the free edge of the gate by pivot pins 37.

Mounted on the pivot pins 37 between the locking members 34 and the edge of the gate is an auxiliary locking member 38, a stop 39 on the gate preventing a full rotative movement of the auxiliary locking member. The edge of the locking member 34 remote from the gate and both edges of the auxiliary locking member 38 are provided with hooks 40 adapted to seat in a recess 41 formed in the inner surface of the front wall of the wardrobe section. As the gate may be secured in either of the openings 32 in the bracket, the respective locking members are provided to insure the locking of the free edge of the gate in any pivotal mounting of the latter.

As previously stated, the top wall of the wardrobe section and the front wall thereof from a point above the space 5 is cut away to receive the corresponding parts of the drawer section when the latter is closed. The space closed by the remaining portion of the front wall provides a compartment space and in the front and rear walls of the wardrobe section, within the dimensions of this space, are provided transversely arranged channels 42 of which, of course, there may be any appropriate number. These channels are connected at their rear ends to a vertical channel 43 by inclined channel formations 44 constituting an uninterrupted

passage from each horizontal channel to the vertical channel. The compartments are formed by floor sections 45 made up of hinged strips 46, 47 having pins 48 to seat in the opposed channels. With the compartments at their maximum length, the floor sections rest in the horizontal channel and when it is desired to reduce this length, the pins of the rearmost floor section are directed into the inclined channels 44 and the floor section moved rearwardly so that finally the compartment is of a length corresponding to the width of the outermost end floor section, as clearly shown in dotted lines in Figure 7.

To complete the compartment section, there is provided a closure 49 designed to form the forward wall of the compartment section, this closure being in the form of a panel and provided with openings 50 with or without independent closures therefor to permit access to the respective compartments. This closure is also adjustable relative to the compartments, being provided with lateral pins 51 sliding in longitudinal channels 52 in the side walls of the trunk, each of said channels being formed at its respective ends with depending short channels 53 and 54 respectively. Obviously, with the closure arranged so that its pins 51 are in the short depending channels 53, the compartments are of their full length, while if the floor sections are moved rearwardly as described, the closure may be correspondingly moved rearwardly until its pins 51 drop into the short channels 54. Thus, the closure may be made effective for compartments of full size or, in the event the garment hangers are so filled as to require additional garment space, the compartments may be reduced in size to provide this space while yet affording effective compartments.

It is, of course, apparent that the wardrobe section, insofar as the garment hangers are concerned, is adapted to support garments in the usual manner, the hangers being slideable in groups and independently swingable to permit access to a particular garment. When the garment hangers have been supplied and it is desired to hold the garments thereon against undue movement during shipment of the trunk, the gate is mounted in the appropriate openings 32 in the brackets 17 and 18 and swung across the front of the garments, being thereafter held in this position by the cooperation of the hooks 40 of either the main or auxiliary locking bar, with the sockets 41 in the trunk walls.

What I claim to be new is:

1. A wardrobe trunk including a drawer section, a wardrobe section, hangers slideable in the wardrobe section, and a series of compartments arranged below the hangers, said compartments being adjustable as to size to

vary the space permitted the garments supported on the hangers.

2. A wardrobe trunk including a drawer section, a wardrobe section, hangers slideable in the wardrobe section, a series of compartments arranged below the hangers, said compartments being adjustable as to size to vary the space permitted the garments supported on the hangers, and an adjustable gate for 10 overlying the garments supported on the hangers.

3. In a wardrobe trunk, a drawer section, a wardrobe section, hangers movable in the wardrobe, a series of compartments arranged 15 in the wardrobe section below the hangers, a closure for said compartments, means for adjusting the depth of the compartments at will, and means for moving the closure to cooperate with the adjusted depth of the 20 compartments.

4. In a wardrobe trunk, a drawer section, a wardrobe section, hangers movable in the wardrobe, a series of compartments arranged in the wardrobe section below the hangers, 25 a closure for said compartments, means for adjusting the length of the compartments at will, means for moving the closure to cooperate with the adjusted length of the compartments, and means for locking the closure 30 in adjusted position.

5. In a wardrobe trunk, a wardrobe section, hangers slidably mounted in the upper

portion of said section, a plurality of compartments formed in vertical alignment below the hangers, slideable bottoms for said 35 compartments, means to permit movement of the bottoms to vary the depth of the compartments, a closure for the compartments slidably mounted in the walls of the wardrobe section to close the compartments in 40 either of their adjusted lengths, and means whereby the closure may be locked in either of its adjusted positions.

6. In a wardrobe trunk, a wardrobe section, hangers slidably mounted in the upper 45 portion of said section, a plurality of compartments formed in vertical alignment below the hangers, slideable bottoms for said compartments, means to permit movement of the bottoms to vary the depth of the compartments, a closure cooperating with all 50 of said compartments and formed with lateral pins to slide in slots in the walls of the trunk, whereby the closure may be moved to serve as a closure for the compartments in either size adjustment of the latter, the slots in the trunk walls for receiving 55 the closure pins being formed at appropriate points with depending communicating channel sections to receive the pins and lock the closure in either of its adjusted positions.

In testimony whereof I affix my signature.

ORVIL G. LEMMER.
